UNITED STATES PATENT OFFICE

RICHARD SHERWIN, OF TORONTO, ONTARIO, CANADA

GAUGE POLE

Application filed February 11, 1929. Serial No. 339,160.

This invention relates to gauge poles for cutting the hinge seats and mortises in doors and door frames. An object of the invention is to provide a device of this nature which will enable one to properly locate the hinges on a door so that the hinges on the door and frame of the same sides will be positioned to hang the door squarely in its frame.

Another object of the invention is to provide a gauge pole of this nature which is adapted to rout the mortise for a lock on the door and frame so as to facilitate the proper insertion when the door is hung in position.

Another object of the invention is to provide a pole which is extensible to meet the requirements of any sized door with respect to the length and thickness thereof and to provide for demounting a section of the gauge pole so that the same may be adapted to locate the hinges on smaller closures, such as transoms, swinging windows or the like.

Other objects of the invention of a gauge pole of this nature which is very simple in its construction and assembly, is easy to manipulate, efficient for its intended purpose, strong and durable, thoroughly reliable for its intended use, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications may be resorted to which fall within the scope of the claims hereunto appended.

In the drawings, wherein like reference characters denote corresponding parts throughout the several views:

Figure 1 is a perspective view, partly broken away, of a door frame illustrating an adaptation therewith of the device in accordance with this invention.

Figure 2 is a perspective view of a door resting on its longitudinal edge and illustrating an adaptation therewith of the device in accordance with the invention.

Figure 3 is a perspective view, broken

away, showing the construction of the bottom templet of the device,

Figure 4 is a front elevation, partly broken away illustrating the top of the device in accordance with this invention,

Figure 5 is a bottom plan view of a power driven router modified to cooperate with the gauge pole in accordance with this invention,

Figure 6 is a side view of Figure 4,

Figure 7 is a front elevation of the templet bars detached from the gauge pole and positioned with respect to each other as they are located on the gauge pole,

Figure 8 is a sectional view through the templet bars illustrating the position of the routing tool on the templet bars and furthermore illustrating in dotted lines the edge of the door being cut out to receive the hinge,

Figure 9 is a section taken on line 9—9 of Figure 2 and looking in the direction of the arrows,

Figure 10 is a detail sectional view of the support member with the device.

This invention is an improvement on my gauge pole for hinging doors U. S. Letters Patent #1,612,068, patented December 28, 1926.

Referring to the drawings in detail, it will be seen that the body of the gauge is formed of a plurality of templets A, B and C disposed in longitudinally aligned, end to end relation. The middle templet B is detachable from the upper templet A and lower templet C, so that the gauge may be used in connection with building units of less length than doors.

Each templet is formed of a pair of parallel, spaced right angled bars, 40, 41 having the angles confronting each other. The spaces between the angle bars define the portion of the doors to be routed to receive hinges, or to be mortised to receive locks. These angle bars are fixed in parallel relation to each other.

Middle templet B has slotted tongues 17, 18 projecting from its opposite ends that extend into the inner ends of the upper and lower sleeves 19 and 20. The inner ends of these tongues 17 and 18 are disposed across the confronting angles at the opposite ends

of the angle bars 40, 41, of templet B and are secured thereto by screws 43. The upper templet A has a slotted tongue 15 secured at its inner end to the inner ends of the angle bars of templet A, in the same manner as tongues 17 and 18.

This tongue projects from the lower end of templet A and its outer end extends into the outer end of upper sleeve 19. Projecting from the upper end of lower templet C is a slotted tongue 16 that extends into the outer end of lower sleeve 20. Tongue 16 is anchored to the upper ends of the angle bars of their templet C like the other tongues. These templets are adjustable with respect to each other by moving the slotted tongues in or out of the sleeves as desired and locking them in adjusted position with the thumb screws 21 and 22 on the opposite ends of the sleeves. When it is desired to make the gauge shorter, the middle templet B and one sleeve may be removed entirely from the assembly shown in Figs. 1 and 2 of the drawings.

25 An adjustable arm 25' extends from the upper end of upper templet A and on the free end thereof is anchored a right angled flange 23. Slidably seated in a recess on one leg of this flange is a countersunk plate 24 that is flush with the face of that leg of the flange in which it is seated. When the gauge is used in conjunction with door frames H', as shown in Fig. 1, the plate is seated in the recess in the flange, but when the gauge is used with door H, the plate is extended from the recess to overlap the upper corner of the door H as will be seen from Fig. 2 of the drawings.

From the lower end of lever templet C there extends an adjustable arm 25 and has formed on one face, a laterally projecting lug 26 that is adjacent the lower end of the arm. Extending through a threaded opening in the lug is an adjustment screw 27 that has a flat rest plate 28 on its lower end adapted to engage the floor when the gauge is used in conjunction with the door frame; otherwise, this plate rest may be moved inwardly against the lug when the gauge is used on a door.

50 Spaced from the adjusting screw is a bolt 31 that is slidable in an opening in the lug 26. One end of a bowed plate spring 30 is secured to the lug 26 and the other end engages the head of bolt 31 for normally urging the bolt upwardly. On the outer end of bolt 31 is a flat bar 29 that clamps over the lower corner of a door when the bolt is extended as shown in Fig. 2. When the gauge is not used on a door, the bar will seat in a pocket in the lower face of lug 26 when bolt 31 is turned in a manner similar to the other clamps to be presently described. The inner ends of arms 25—25' are secured to the outer ends of the templet bars 40, 41 of templets C

and A in the same manner that the tongues are secured thereto.

Adjacent each templet A, B and C, are gripping members indicated generally at 32, 33 and 34. These gripping members are coupled with the templets and are adapted to swing to a position at right angles to the body of the gauge and engage the one side face of a door H at spaced intervals.

Since each of the gripping members is formed in the same manner, it is believed that the following description directed to one of the gripping members will give a clear understanding of the others. Each gripping member consists of a bolt 35 pivoted at one end to an upstanding lug 36 that threadably engages with the respective arms and tongues. This lug 36 as shown is detachably secured to arms 25 and 25' for the upper and lower gripping members, whereas the lug 36 is for the middle gripping member 33 is anchored to slotted tongue 18.

A substantially L-shaped foot 38 is slidable on the shank of each bolt 35 and this foot is resiliently held in engagement with the door by one end of a coil spring 39, composed about the shank of the bolt, while the other end of the spring is held by a wing nut 37 threaded on the free end of the bolt. The gripping members may be removed by unscrewing the lugs 36.

The inner faces of one angle bar 40 for each templet, are graduated in inches and fractions of inches as at 42 and the graduations continue over the upper edge of the vertical leg of each bar. Adjacent each end, the angle bars on the same side of each templet, support a pair of clamps 44 formed on the ends of sliding and rotatable bolts similar in all respects to the bolt 31 heretofore described.

These clamps 44, when not in use, are seated in recesses 45 in the outer face of the vertical legs of the angle bars to which they are attached. In extended relation, these clamps hold the body of the gauge flush with the one face of the door opposed to the face engaged by the gripping members.

Each templet has a fixed abutment plate 46 adjacent one end and a movable abutment plate 47 adjacent the other end. These abutment plates are right angled in cross section with the angles thereof oppositely directed. Moreover, these abutment plates are disposed transversely of and rest in confronting angles of the bars 40 and 41. The vertical legs of the abutment plates define the area of the recess to be routed for the hinges. The horizontal legs of the fixed abutment plates are secured to the horizontal legs of the side bars of the templets by screws 48. The horizontal legs of the movable abutment plates 47 are secured to the inner ends of slotted plates 49 that slide in the space between the side angle bars under the respective slotted tongues 15, 16

and 17. The sliding plates 49 are locked in any position by means of a thumb screw 50.

To the bottom of the motor driven router R is secured a plate 51 that is flat. In the center the plate is formed with an opening to permit the routing tool T to extend therethrough and from the central opening the bottom face of the plate is formed with a groove 52 that extends in opposite directions to the outer ends of the plate.

Adjacent the slot on either side are graduations 54 which cooperate with an arrow 55 formed on the outwardly disposed leg 56 of the guide member 53 in any position with respect to the groove. The guide member 53 is a flat bar that depends below the plate 51 and abuts against the vertical leg of the side angle bars 40, 41 depending upon which side of the plate 51 the guide is disposed.

It will be understood that the guide 53 is adapted to be positioned on either side of the routing tool. Thus it will be seen that the distance from the routing tool to the guide 53 will determine the width of the hinge seat, while the distance between abutment 46, and 47 will determine the length of the hinge seat to be routed out of the edge of the door H.

In the application of the invention, the templets A, B and C are adjusted to approximate positions of the hinges on the frame H'. Plate 24 is moved into its recess on flange 23 and the body of the gauge is disposed against the side of the frame screwing down on bolt 27 until plate 28 abuts the floor. Then the bridge pole P is placed across the frame with one end engaged with the other side of frame H' and the other end abutting the body of the gauge intermediate the ends. This bridge pole is formed of a pair of rods 59 and 62. The one section 59 is formed with a socket 61 in one end, in which is seated a coil spring 60 that bears against the inner end of rod 62 that telescopically fits into the socket. A pin 63 is anchored in the end of section 62 and extends through a slot 64 in the wall of socket 61 to limit the movement of the rods with respect to each other.

Having positioned the gauge on the frame H', movable abutment plate 47 on each templet A, B and C, is adjusted to the length of the hinge seat to be routed. Next, the guide plate 53 on the router R is set to the width of the hinge. Then the router is applied to each templets A, B and C within the limits of abutment plates 46, 47 and to such a width until the guide plate 53 abuts the upstanding leg of the side angle bar. With the same adjustment, the body of the gauge is then transferred to the door and the hinge seats on the door are cut with one and the same setting, insuring matching of the hinges.

It will be understood that a mortise for a door lock and its keeper may be made by

an application of the central templet B in the same manner as described for hinge seats.

Having thus described my invention, what I claim as new is:

1. A gauge pole of the class described comprising a plurality of templets disposed in end to end relation, said templets formed of longitudinally extending spaced angle bars, tongues secured at their inner ends to the confronting ends of each templet, means for adjustably connecting the confronting free ends of the tongues together, a pair of abutment plates mounted across the angle bars on each templet, one of said abutment plates being adjustable with respect to said angle bars, an adjustable arm secured to the outer end of each of the outermost templets, means associated with the outer end of each arm for gripping certain corners of a door, and gripping members and clamps on the opposite side of the templets for engaging the opposite sides of a door.

2. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, and abutment plates supported on said bars for limiting the length of the free space between the bars.

3. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, and abutment plates supported on said bars for limiting the length of the free space between the bars, and retractile clamps on one side and pivoted gripping member on the other side of said templets for engaging the opposite faces of a door.

4. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, abutment plates supported on said bars for limiting the length of the free space between the bars, retractile clamps on one side and pivoted gripping member on the other side of said templets for engaging the opposite faces of a door, and said bars being angular in cross

section with the angles confronting each other.

5. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, abutment plates supported on said bars for limiting the length of the free space between the bars, retractile clamps on one side and pivoted gripping member on the other side of said templets for engaging the opposite faces of a door, said bars being angular in cross section with the angles confronting each other, and said abutment plates being angular in cross section with the angles thereof oppositely directed.

6. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, abutment plates supported on said bars for limiting the length of the free space between the bars, and one of said abutment plates being fixed and the other movable.

7. A gauge pole of the character described comprising a plurality of templets disposed in end to end relation, said templets formed of spaced bars, interconnected means on the confronting ends of the templets for adjustably connecting the templets together, adjustable means on the outer ends of the outermost templets adapted for gripping the building structure being operated upon, abutment plates supported on said bars for limiting the length of the free space between the bars, retractile clamps on one side, and pivoted gripping members on the other side of said templets for engaging the opposite faces of a door, and one of said abutment plates being fixed and the other movable.

In testimony whereof I affix my signature.
RICHARD SHERWIN.
